METHOD OF AND MEANS FOR FASTENING
SPRINGS TOGETHERCharles Dietrich, Cleveland, Ohio, assignor to
The Owen Silent Spring Company, Inc., Bridge-
port, Conn., a corporation of Connecticut

Application August 13, 1932, Serial No. 628,635

7 Claims. (Cl. 140—3)

The present invention relates to improvements in method of and means for fastening springs together to form spring structures, such, for instance, as those used in bed or chair bottoms or as the resilient cores of mattresses or cushions.

It is common practice in such structures to fasten the springs to tie wire by means of clips, and special machines are provided for forming and attaching the clips because it is an awkward and time consuming task to apply the clips with hand tools and also because the operation of locking the clips securely to the spring elements calls for the exercise of considerable effort.

For these reasons it has been customary to clip the springs together at the factory and then to ship them assembled to mattress or furniture manufacturers. However, the space taken up by assembled spring structures of this character, both in storage and transportation, is objectionable and adds materially to the cost of the finished product.

In my Patent No. 1,854,503, issued April 19th, 1932, I describe a method of and means for assembling springs, that calls for no complicated assembling machinery. A special form tie wire is employed which is bent to form off-set loops. In these off-sets adjacent spring sections may be seated and then the off-sets are bent over and clamped upon the spring sections by means of pliers. This permits of shipping the springs and tie wires separately to mattress and furniture manufacturers and the latter may then assemble them in accordance with their sales demands.

One drawback of the system disclosed in my said patent is the fact that hand tools have to be employed to clamp the loop off-sets upon the springs.

The present invention has for an object to provide a novel system of assembly which may be carried out without the use of any hand tools. Thus, the assembling of spring structures is greatly simplified and expedited and can be performed with lower-priced operatives.

More specifically my invention has for an object to provide a tie wire bent to form hooks thereon which are of such form and relative disposition that the spring parts to be connected may be introduced therein in a special manner and once in place will not separate therefrom under the most severe service conditions.

Another object of the invention is to provide a tie wire of the character described above in which the spring parts are so connected that there can be no rattling of one part against another.

Another object of the invention is to provide a spring connection in which the tie wire will be fastened securely to one of the springs while the other will have a hinged connection therewith.

While it is preferable to employ tie wires to connect the springs my invention also contemplates the provision of individual clips formed with hooks of the same general character as those employed in the tie wire.

Other objects and advantages of my invention will appear in the following description of a preferred embodiment thereof and mode of assembly and thereafter the novelty and scope of the invention will be pointed out in the claims.

In the accompanying drawings:

Figure 1 is a fragmental plan view of a spring structure showing a plurality of coil springs connected by means of my improved tie wires;

Fig. 2 is a view in section taken on the line 2—2 of Fig. 1 and enlarged;

Fig. 3 is a plan view on an enlarged scale showing two springs connected by a tie wire;

Figs. 4, 5, and 6 are fragmental views in perspective showing successive steps in the attachment of a pair of springs to a tie wire; and

Fig. 7 is a view in side elevation showing the manner of attaching the upper end of a spring whose lower end has already been made fast to a spring structure.

My invention is applicable to helical springs of either the closed or the open end coil type. In Fig. 1, I show a part of a mattress structure composed of open end coil springs 10 with a row of closed end coil springs 11 at each end of the structure. The springs are connected by my improved tie wires 12 which extend between adjacent rows of springs. Similar tie wires 13 are provided at each end of the structure to serve as border wires. The tie wires are preferably provided both at the top and bottom of the spring structure, as shown in Fig. 2, so that each coil spring will be anchored at each end thereof.

Each tie wire is formed at intervals with a set of three hooks, namely, a central hook 15 and a pair of opposed outer hooks 16 and 17 disposed respectively on opposite sides of the central hook. In Fig. 3 the hooks are shown on an enlarged scale connecting end coils 10a and 11a of a pair of springs 10 and 11 respectively. It will be observed that each hook is formed of a U-shaped portion of the tie wire which is bent laterally out of alignment with the tie wire and then is bent upward and inward to form a hook. Thus, each hook really comprises two wire elements integrally connected at the nib or free end of the

hook. The bight of each hook comprises two spaced recesses which are indicated at 15a, 16a, and 17a in the hooks 15, 16 and 17 respectively. It will be observed that the hooks 16 and 17 although facing in opposed direction to hook 15, diverge from parallelism therewith, so that the bight of each hook 16 and 17 will be disposed substantially tangent to the end coil 10a. The relative size and disposition of the hooks is such that when the spring coils 10a and 11a are connected said coils will be in snug tangential engagement with the wire of coil 11a seated firmly in the recesses 15a and that of coil 10a seated firmly in the recesses 16a and 17a.

15 The nib 15c of hook 15 preferably laps over the adjacent portion of coil 10a and thereby prevents the latter from working out of engagement with the loops 16 and 17 and at the same time prevents the coil 11a from slipping out of engagement with hook 15. The various parts are held snugly in engagement with one another so that there is no rattling of the spring members against the tie wire or against each other. The free end 10b of the coil 10a is bent off at a decided angle, as shown in Fig. 3, so that it cannot pull lengthwise out of engagement with the hooks 16 and 17. It will be observed that this mode of connection permits the spring section 11a to hinge freely in the bight of the hook 15, while the spring section 10a is substantially fixed to the tie wire, and can turn with difficulty in the hooks 16 and 17. While the relative size and disposition of the hooks depends upon the wire gauge and diameter of the coils to be connected an appreciable tolerance is permissible due to the resiliency of the spring and tie wires so that a given tie wire may be used with springs that vary somewhat in gauge or diameter.

30 The mode of assembling the springs is as follows: An end coil 11a of a spring 11 is first inserted into the hook 15. Then an end coil 10a of a spring 10 is applied by first catching its free end under the hook 16 and then under hook 15. This is facilitated by swinging the end coil 10a to a position substantially perpendicular to the plane of the coil 11a, as shown in Fig. 4, although the hooks 16 and 15 can be engaged without swinging the coil upward as shown. However, before the next hook 17 can be engaged it will be found essential to swing the coil 10a to the position shown in Figs. 4 and 5 so that it may be sprung past and under the nib 17c of hook 17. Thereafter the end coil 10a is swung down into the plane of the coil 11a, as shown in Fig. 6. Fig. 5 shows in broken lines the position of coil 10a after it has been swung substantially perpendicular to coil 11a and has been hooked under hooks 15 and 16. It will be observed that the coil is given a lateral twist with respect to the wire 12 so that it will clear the nib 17c. Then it is flexed downwardly and passed under the nib before it is swung down to normal position. In order to permit of such an assembly of the parts it is essential that the space between the spring wire seated in the bight of the hook 15 and the adjacent sides 16b and 17b of the hooks 16 and 17, must be somewhat wider than the diameter of the wire of the spring coil 10a. Preferably the sides 16b and 17b are substantially parallel to the adjacent sections of the coil 11a.

Fig. 7 shows how the upper end of a spring 10 is introduced into the hooks of an upper tie wire when the lower end of the spring has already been attached to the spring structure. Since the heli-

cal springs are very resilient it is a comparatively simple matter to bend the upper end loop 10a of the spring 10 substantially at right angles to the corresponding coil 11a of the adjacent spring 11 and then the mode of assembly is exactly the same as that described and shown in Figs. 4 to 6 inclusive.

Once the springs have been connected in the manner shown it is impossible to separate them without bending the coil engaged by loops 16 and 17 to substantially 90 degrees from its normal position and even then it must be twisted laterally in order to slip it out of engagement with these hooks. Since in service the springs never assume the relative positions shown in Fig. 7 there is no danger of separation of a spring from the connecting tie wire unless such separation is intentionally produced.

When springs with closed end coils are connected to the tie wire the procedure is the same as with open end springs. It is not necessary to have a free end for initial insertion in hook 16. The attachment may be made to any part of a spring coil whether open or closed. Although in the preferred embodiment of my invention, I employ the wires with sets of hooks formed thereon at intervals, obviously individual clips may be formed by omitting the connecting length of wire extending between the sets of hooks.

While I have described a preferred embodiment of my invention, it will be understood that this is to be taken as illustrative and not as limitative and that I reserve the right to make such variations in form, structure, arrangement of parts and mode of assembly as fall within the spirit and scope of the following claims.

I claim:

1. A tie for connecting coil springs, comprising a pair of outer open hooks in which a wire section of one of the springs may be seated, and an opposed intermediate open hook in which a wire section of the other of the springs may be seated, the hooks being integrally connected and relatively spaced to hold the two wire sections in snug tangential engagement and the spacing between the intermediate hook and each outer hook being greater than the combined thickness of the two wire sections.

2. A tie for connecting coil springs, comprising a pair of outer open hooks in which a wire section of one of the springs may be seated, and an opposed intermediate open hook in which a wire section of the other of the springs may be seated, the hooks being integrally connected and relatively spaced to hold the two wire sections in snug tangential engagement, with the nib of the intermediate hook overlapping both of the wire sections and the spacing between the intermediate hook and each outer hook being greater than the combined thickness of the two wire sections.

3. A tie for connecting coil springs, comprising a pair of outer open hooks in which a wire section of one of the springs may be seated, and an opposed intermediate open hook in which a wire section of the other of the springs may be seated, the hooks being integrally connected and relatively spaced to hold the two wire sections in snug tangential engagement, with the nib of the intermediate hook overlapping both of the wire sections and the spacing between the intermediate hook and each outer hook being greater than the combined thickness of the two wire sections, the bight of each hook being tangential to the wire section seated therein.

4. A tie for connecting coil springs, comprising

ing a pair of outer hooks in which a wire section of one of the springs may be seated, and an opposed intermediate hook in which a wire section of the other of the springs may be seated, the 5 hooks being integrally connected and relatively spaced to hold the two wire sections in snug tangential engagement with the nib of the intermediate hook overlapping both of the wire sections, the bight of each hook being tangential to the 10 wire section seated therein, and the inner sides of the nibs of the outer hooks being disposed substantially parallel to adjacent portions of the wire section seated in the intermediate hook but separated therefrom by a space exceeding the 15 thickness of the wire section seated in the outer hooks.

5. A spring structure comprising a pair of coil springs and a tie connecting an end coil of one of the springs to an end coil of the other, said 20 tie comprising an open hook in which a wire section of one coil is seated and a pair of opposed open hooks in which a wire section of the other coil is seated, the hooks being relatively spaced to hold the two wire sections in snug tangential 25 engagement with the nib of the first-named or intermediate hook overlapping both of the wire sections, and the spacing between the intermediate hook and each outer hook being greater than the combined thickness of the two wire sec- 30 tions, one of said end coils being open and having

the free end thereof bent laterally to prevent the wire from pulling out lengthwise through hooks.

6. The method of attaching a pair of spring coils to a tie member formed with a pair of outer hooks and an opposed intermediate hook so relatively disposed as to hold the two coils, when attached, in snug tangential engagement, which comprises the steps of hooking one of the coils into said intermediate hook, hooking the second coil into one of the outer hooks and under 10 the intermediate hook against the first coil, tilting the second coil into a plane substantially perpendicular to that of the first coil, flexing the tilted coil under the other of the outer hooks and then swinging the tilted coil back into the plane 15 of the first coil.

7. The method of attaching a pair of spring coils to a tie member having a pair of outer hooks and an opposed intermediate hook so relatively disposed as to hold the two coils, when assembled, 20 in snug tangential engagement, which includes the steps of hooking one of the coils into said intermediate hook, tilting the other coil into a plane substantially perpendicular to that of the first-named coil, catching the tilted coil successively under one of the outer hooks, the intermediate hook and the other outer hook, and then 25 swinging the tilted coil into the plane of the first-named coil.

CHARLES DIETRICH. 30
